DESIGN FOR A HANDGRIP FOR WASHING MACHINE COVER OR THE LIKE

Arthur P. Schulz, Hinsdale, Ill., assignor to Electric Household Utilities Corporation, Chicago, Ill., a corporation of Illinois

Application February 4, 1944, Serial No. 112,435

Term of patent 3½ years

(Cl. D49—1)

To all whom it may concern:

Be it known that I, Arthur P. Schulz, a citizen of the United States, residing at Hinsdale, in the county of Du Page and State of Illinois, have invented a new, original, and ornamental Design for a Handgrip for Washing Machine Cover or the Like, of which the following is a specification, reference being had to the accompanying drawing, forming a part thereof.

In the drawing:

Fig. 1 is a top or face view of a handgrip for washing machine cover or the like and embodying my new design;

Fig. 2 is a cross-sectional view, taken on line 2—2 of Fig. 1; and

Fig. 3 is a side elevational view thereof.

I claim:

The ornamental design for a handgrip for washing machine cover or the like, substantially as shown.

ARTHUR P. SCHULZ.
